G. I. WORLEY AND C. E. LOGAN.

OIL TANK HEATER.

APPLICATION FILED JULY 13, 1917.

1,361,212.

Patented Dec. 7, 1920.

UNITED STATES PATENT OFFICE.

GEORGE I. WORLEY AND CHARLES E. LOGAN, OF KANSAS CITY, MISSOURI, ASSIGNORS TO THE GOOD ROADS CO., OF KANSAS CITY, MISSOURI, A CORPORATION OF MISSOURI.

OIL-TANK HEATER.

1,361,212.

Specification of Letters Patent. Patented Dec. 7, 1920.

Application filed July 13, 1917. Serial No. 180,449.

To all whom it may concern:

Be it known that we, GEORGE I. WORLEY and CHARLES E. LOGAN, citizens of the United States, residing at Kansas City, in the county of Jackson and State of Missouri, have invented certain new and useful Improvements in Oil-Tank Heaters, of which the following is a specification.

This invention relates to oil tank heaters and more especially to heaters for portable oil tanks of that class employed for oiling roadways. The objects of the invention are to produce a heater by which the whole body of the oil or the like can be raised to any required degree of temperature without generating gas from the oil and therefore without danger of explosion; to produce a heater which can be utilized to heat the oil in the tank regardless of the quantity and as it is being supplied to the tank, as distinguished from those heaters in which the tank must be charged with oil before the heater is started in operation; and to produce a heater having a boiler through which heat is transmitted to oil in the tank to heat the same and from which boiler steam may be supplied to the tank to clean the same.

With these general objects in view, and others as hereinafter appear, the invention consists in certain novel and useful features of construction and combinations of parts as hereinafter described and claimed; and in order that it may be fully understood reference is to be had to the accompanying drawing, in which:

Figure 1, is a view partly in side elevation and partly in central vertical section of an oil tank heater embodying the invention.

Fig. 2, is a rear end view of the same.

Fig. 3, is a cross section on the line III—III of Fig. 1.

Fig. 4, is a cross section on the line IV—IV of Fig. 1.

Referring to the drawing in detail, 1 indicates an oil tank preferably in the form of a horizontally-arranged cylinder and said tank is equipped with a filling tube 2 and with a suitable valve-controlled discharge pipe 3.

Arranged horizontally within and longitudinally of the tank is a heater comprising an inner cylinder 4 forming a combustion

chamber and an outer or surrounding cylinder 5 constituting a boiler, the cylinder 4 projecting through the rear end of the cylinder 5 and the latter through the corresponding end or head of the tank, the joint being made liquid tight in any approved manner.

The cylinder 4 is provided with a smoke stack 6 extending up through the tank and the boiler is likewise provided with an upwardly projecting extension 7 inclosing the smoke stack to the top of the tank and is provided with a closure cap 8, at such point, the upper part of the boiler extension 7 constituting a steam dome. Leading from said steam dome is a steam line 9 equipped with a steam gage 10 and terminating in branch pipes 11 and 12, the former communicating with the boiler at its upper side and rear end, and the branch pipe 12 with the said boiler at a lower point, the said branch pipe 12 containing a water column 13 extending considerably above the plane of the cylinder 5 for the purpose of indicating the height at which the water stands in the extension 7 of the boiler, it being desirable to maintain the water level sufficiently high to protect the cylinder 4 when the tank is inclined in descending or ascending grades, as combustion in cylinder 4 is injurious if the cylinder is not completely immersed in the water.

Fitted against the rear end of the cylinder 4 and secured by bolts 14 to lugs 15 secured in the said cylinder, is a cap 16 provided with a large air-inlet opening 17 and a pair of sleeves 18 and 19.

A gas generator and burner is carried by said cap and is constructed as follows:

20 is a short vertical tube arranged in the cylinder 4 rearward of the boiler tubes and provided with a rearwardly projecting tubular stem 21 closed at its rear end by a cap 22. The tube 20 depends from an elbow 23 secured to the front end of a tube 24 extending longitudinally of and through the sleeve 18 and rearward of the latter is bent downward to semi-circular form and at its lower end extends through the sleeve 19 and terminates in a forwardly projecting nozzle 25 disposed rearward of and in a slightly lower plane than the tubular stem 21 of tube 20.

26 is a pipe for discharging air under

pressure into the tank above the oil therein. 27 is a pipe leading from the chamber of the tank above the oil to the distributing nozzle 27^a, with which the discharge pipe 3 is provided, it being understood that the distributing nozzle is a combined oil and air nozzle, supplied respectively by pipes 3 and 27 and that the pressure of air passing through pipe 27 acts to effect ejection and 10 atomization of oil supplied by pipe 3, the atomized oil being discharged from said nozzle onto the road. The nozzle is not detailed as it is described and shown in Patent No. 1,093,818 of April 21, 1914, for road 15 oiling vehicle, George I. Worley, inventor.

To utilize air under pressure from the upper part of the tank to atomize oil employed as a fuel in the heating operation, a valve-controlled pipe 28 taps pipe 27 and 20 leads through the cap 16 and into the nozzle 29 fitted on the nozzle 25 so that the air under pressure in passing through the nozzle 29 shall exert a suctional action to draw the oil through the nozzle 25 and atomize such 25 oil as it escapes from the nozzle 29, the oil being supplied to the burner from a suitable source not shown, through a valve-controlled supply pipe 30, which extends through pipe 24 and discharges directly 30 down into tube 20, and is controlled at the rear of the burner by a valve 31.

Assuming that the boiler is charged with water, it will be apparent that the heating 35 operation can be started by inserting a torch or piece of lighted waste into the rear end of the cylinder 4 and then successively opening the air and oil valves so that the oil which is supplied to tube 20 and stem 21 by the pipe 30 will after filling said tube, flow 40 back through tube 24 and thence to the nozzle 25, the suction of the air discharged through nozzle 29 effecting ejection and atomization of such oil and producing a combustible mixture which is ignited by the 45 flame from the torch or waste.

The method described is the preferred method of starting the operation of the heater but it is to be understood that if at the time no air under pressure is available, 50 the oil can be permitted to flow from the nozzles 25 and 29 onto the bottom of the combustion chamber and in unatomized form be ignited by a torch or the like. In either event, the flame and heat impinging 55 on the small tubular stem 21 and the tube 20 will quickly vaporize oil standing therein. Under the preferred method of operation, the instant vaporization begins, the compressed air may be shut off, and the oil 60 supply valve temporarily closed. The gas generated in the burner tubes will supply the pressure necessary to effect the forceful forward discharge of the gas from the nozzles during the entire operation of the 65 heater, the fuel supply valve of course being

reopened to the extent dictated by experience, as soon as the color of the flame indicates to the attendant that the generating action within the burner tubes is established so that the heating operation may 70 continue as long as the supply of oil is maintained.

The heat generated first affects the water in the boiler and the heat therefrom is transmitted to the oil or the like with which the tank may have been previously charged or with which it may be charged while the heating operation is in progress, it being obvious that as the heat is transmitted to the oil only through the boiling water and steam dome, it is impossible for the oil to come in contact with a part so hot as to result in the vaporization of the oil and the danger incidental to such action, this danger being such that with oil tank heaters in 85 which the oil is heated through direct contact with the shell or wall with which the flames come in contact, it is essential that the tank shall be charged before the heating operation begins. It is obvious that any arrangement in which it is necessary to charge the tank with oil before starting the heating operation is relatively slow, as compared with apparatus in which the operation of the heater or the supplying of the oil to the 90 tank can be performed at any convenient time. Furthermore with apparatus of the objectionable character mentioned, it is unsafe to attempt the heating of a volume of oil unless it is ample to cover the entire 100 heater, whereas with apparatus of the character herein illustrated, a small quantity of oil may be heated with celerity and perfect safety and in the actual practice of oiling roads, this advantage will be found to be a 105 practical one, as it frequently occurs that the supply contained in the tank is exhausted just prior to covering the prescribed course and that considerable time could be saved if a small quantity of oil 110 could be placed in the tank and quickly heated to complete the oiling operation in progress.

To clean the tank of oil or the like, so that it may be utilized if desired for discharging water, and also to clean the distributing nozzle, the steam supply pipe 9 is equipped with a branch 32, terminating in valve-controlled branches 33 and 34, respectively leading to the compressed air distributing pipe 27, forward and rearward of the valve 27^b thereof, for supplying the distributing nozzle. By this arrangement steam can be discharged through the distributing nozzle to clean heavy oil or asphaltum therefrom or if desired, steam can be discharged back through pipe 27 into the tank for the purpose of cleaning the walls thereof of heavy oil or asphaltum which would otherwise adhere thereto and thus 130

render it undesirable and perhaps impracticable for a time at least to utilize the tank for water flushing purposes.

We claim:

5 1. In an oil tank heater, a closed oil tank, a boiler extending horizontally in said tank and provided at one end with a tubular dome extending up through the top of the tank, a flue extending longitudinally within the
10 boiler from one end thereof nearly to the other and provided with a stack spaced from the side walls of the dome and extending up through the latter to a point exterior thereto and to the tank, means for generating
15 heat within the flue, a pipe connecting the dome at the top, with the opposite end of the boiler, a steam gage on said pipe, and a by-pass between said pipe and the boiler, including a water column extending from
20 a plane above to a plane intermediate the body of the boiler.

2. In an oil tank heater, a closed oil tank, a boiler extending horizontally in said tank and provided at one end with a tubular
25 dome extending up through the top of the tank, a flue extending longitudinally within the boiler from one end thereof nearly to the other and provided with a stack spaced from the side walls of the dome and extending
30 up through the latter to a point exterior thereto and to the tank, means for generating heat within the flue, a pipe connecting the dome at the top with the opposite end of the boiler, a steam gage on said pipe, a by-
35 pass between said pipe and the boiler, including a water column extending from a

plane above to a plane intermediate the body of the boiler, and means for discharging compressed air into the said flue adjacent the said heat-generating means therein, to 40 vaporize the fuel of said heat-generating means.

3. In an oil tank heater, a closed oil tank, a boiler extending horizontally in said tank and provided at one end with a tubular 45 dome extending up through the top of the tank, a flue extending longitudinally within the boiler from one end thereof nearly to the other and provided with a stack spaced from the side walls of the dome and extending 50 up through the latter to a point exterior thereto and to the tank, means for generating heat within the flue, a pipe connecting the dome at the top with the opposite end of the boiler, a steam gage on said pipe, a by-pass 55 between said pipe and the boiler, including a water column extending from a plane above to a plane intermediate the body of the boiler, means for discharging compressed air into the said flue adjacent the said heat- 60 generating means therein, to vaporize the fuel of said last-named means, a valve in said compressed air-supply means, and valve-controlled pipes connected to said compressed air-supply means at opposite 65 sides of the said valve thereof and to the steam supply pipe.

In testimony whereof, we affix our signatures.

GEORGE I. WORLEY.
CHARLES E. LOGAN.
